UNITED STATES PATENT OFFICE.

IRVING J. BALL, OF BROCK, NEBRASKA.

CORN GATHERING AND HUSKING MACHINE.

No. 834,246.

Specification of Letters Patent.

Patented Oct. 30, 1906.

Application filed October 15, 1904. Serial No. 228,540.

To all whom it may concern:

Be it known that I, IRVING J. BALL, a citizen of the United States, residing at Brock, in the county of Nemaha and State of Nebraska, have invented certain new and useful Improvements in Corn Gathering and Husking Machines, of which the following is a specification, reference being had therein to the accompanying drawings.

This invention relates to a machine for gathering and husking corn, and has for its primary object the provision of a machine of this character designed more particularly for use upon the field and whereby the corn may be removed from their stalks without necessitating the cutting of the latter during the travel of the machine over said field and also whereby in a continuous operation the husks may be removed from the various ears and separated therefrom.

An advantageous characteristic of the invention resides in the peculiar manipulation of the ears in the different steps of the operation of the machine, whereby the same resembles as near as possible the more usual hand method of husking, so that the complete or clean husking of the ears is practically assured.

Novel features of a machine constituting a convenient embodiment of the invention embrace means for causing the stalks to approach or rest upon the ground, means for separating the ears from the stalks, means for removing the butts of the ears, means for endwise reversing the ears to cause them to travel in the proper direction relative to the husking instrumentalities, means for removing the husks from one side of the ears, means for presenting the opposite side of the ears to other husking instrumentalities, in combination with the latter, and means whereby the cleaned ears and the husks are separated and conducted to predetermined points of discharge from the machine, the means for receiving the shucked ears being preferably a conveyer arranged to carry the same to a wagon in front of the machine, and through the medium of which the machine is drawn over the field.

All of the foregoing, as well as many other novel features of the invention, incident to the construction and arrangement of the several parts of the machine, will be apparent from the detailed description hereinafter

when read in connection with the accompanying drawings, forming part hereof, and wherein in the above-mentioned convenient embodiment of the invention is illustrated.

In the drawings, Figure 1 is a side elevation of the complete machine. Fig. 2 is a longitudinal vertical section. Fig. 3 is a bottom plan view. Fig. 4 is a rear elevation. Fig. 5 is an enlarged sectional view of the initial husking means with the immediately-associated parts of the machine. Fig. 6 is a similar view of the second or final husking means with the immediately-associated parts of the machine. Fig. 7 is a detail perspective view, partly in section, of the guide-fingers and cutters employed for separating the ears from the stalks and for cutting away any obstructions disposed transversely to the line of travel of the machine. Fig. 8 is a sectional view of one of the yieldable bearings; and Fig. 9 is a detail perspective view, the parts being shown as separated, of one of the bearings for supporting wheels for the rear of the machine.

Referring more specifically to the drawings, wherein like reference characters refer to corresponding parts in the several views, A designates the frame of the machine, the same having a slight forward pitch for a purpose to be hereinafter noted.

B represents the main traction-wheels, which may be of any desired type having a smooth, roughened, or toothed periphery, as ordinary in this class of machines.

C represents caster-wheels for supporting the rear portion of the machine, these wheels being adjustable to give the proper elevation to the machine relative to the ground, such adjustment being permitted and maintained by means of rotatably-mounted shanks or stems c, carrying the wheels at one end and at their opposite or upper end being provided with a series of disks or flanges c', substantially circular in contour and loosely fitting correspondingly-grooved bearing-boxes C', secured to the rearmost beams of the frame A. The bearing-boxes are split, as clearly illustrated in Fig. 9, the two members of each being hinged together, as at c'', and locked with the shanks c in adjusted position therein, by bolts and nuts c². This feature of the invention I will not claim herein, inasmuch as the same more properly constitutes subject-matter for a divisional application.

D represents a draft-bar or tongue pivot-

ally secured at a' to the shaft 13 at points adjoining the forward ends of the horizontally-disposed side bars a of the frame A, the free end of this draft-bar or tongue having a link 5 or eye d , whereby the same may be readily attached to a wagon, which latter not constituting a part of the present invention will not be illustrated, it being simply necessary to state that it is through the medium of a 10 wagon and its propelling source of power that the present machine is drawn from place to place over a corn-field, though of course instances may arise when draft-horses may be attached directly to the draft-bar D or other source of power mounted upon the frame of the machine.

It is to be understood that the machine is drawn over the stalks as ordinarily grown in the field and that although the wagon before 15 referred to will primarily bend the stalks somewhat toward the ground I have found it expedient to provide other means for causing said stalks to closely approach or rest upon the ground. The device which I have provided, while in some respects not unlike a harrow, will be hereinafter referred to as a "stalk-bender" or bending device, the meaning intended to be conveyed by such term being that the device is designed to bend the 20 stalks over in the path of the machine without separating them from the ground, whereby the ears may be removed therefrom more quickly and easily than where the stalks are cut, owing to the resistance offered by the 25 fixed relation of said stalks relative to the movement of the machine. The bending device just referred to comprises side bars E, diverging outwardly at their forward ends, as at e , and rigidly connected together by cross-bars e' . Beneath the side bars E are adjustable guide-plates F, their vertical adjustment being afforded through the medium of bolts 30 and nuts f , the former passing through suitable apertures provided therefor in the bars 35 E. The foremost cross-bar e' bends the stalks down close to the ground and the plates F guide the same into proper alinement longitudinally of the machine and relative to other guides, to be shortly described.

Each side bar is also provided with a series of 40 teeth G, the depth of penetration of which into the ground is limited by the plates F, the adjustment of the parts being such that a sufficient portion of each tooth projects beneath the plates F to gather in any loose ears 45 lying upon the ground and in the path thereof. Inasmuch as the draft-bar D must be raised or lowered on its pivot a' in accordance with the size of the wagon to which the 50 same is to be attached, some means must be provided for properly adjusting the stalk-bending device, this means comprising a chain H, secured to one of the intermediate cross-bars e' and arranged to engage over a 55 hook h on a brace h' between the two mem-

bers of said draft-bar. I have referred to one only of these adjusting-chains, although it is my purpose to use two of them, one at each side of the machine. The forward cross-bar e' is connected to the draft-bar or tongue D by flexible connections I, which secure a proper forward movement of the stalk bending and guiding means.

At times—for instance, while turning the machine in the field—it is desirable to elevate the device just described out of engagement with the ground, whereby to preserve the teeth and facilitate the turning movement. Any device may be employed for this purpose, that shown in the present instance comprising a rotatable drum J, Figs. 1 and 2, mounted upon the cross-bar or brace e' , Fig. 2, over which drum works an operating-cable, one end of which is fastened to one of the side bars E, while the other end extends forwardly over the drum to a convenient controlling device, that most commonly at hand being the brake-operating means of the wagon, the latter, however, when used for the present purpose, being deprived of its connection with the brake-shoes, as is obvious.

As the stalks are laid down and straightened longitudinally of the machine they are guided by the plates F to either one of the three ways K beneath the main portion of the machine, formed partially by the flanges k on the transversely-disposed plate k' , partially by side plates L on the frame A, and partially by circumferential ribs or flanges M on a rotatable carrier N, it being observed upon an inspection of Figs. 2 and 3 that the side plates L extend alongside both the rotary carrier and the outer edges of the plate k' and also that the flanges k are in longitudinal alinement with the circumferential ribs or flanges M. By this arrangement three distinct continuous ways K are provided and continually maintained without interfering with the rotary movement of the carrier N, it being understood that any desired number of ways greater or less than three may be provided, in keeping with the principle involved to adapt the machine to any particular use or capacity. Arranged so that the spaces between the same may properly register with the ways K are a series of guide-fingers O, Figs. 2, 5, and 7, the same being broad and flat, though somewhat pointed, and adjustably secured in place in the following manner:

P is a beam fixedly secured across the lower rear end of the machine and provided on its outer face with ribs p , designed to enter complementary grooves p' in the upper face of each guide-finger O. This permits the proper adjustment of the fingers, and to lock the beam and teeth together bolts p'' pass through slots p^2 in the fingers and apertures in the beam, the threaded ends of the bolts being engaged by nuts p^3 . These bolts and nuts serve the additional function of fas-

tening in place the upper ends of vertically-disposed knife-blades Q, said upper ends thereof being indicated at q and slotted, as at q', for the reception of the headed ends q'' of the bolts p''. The lower back edges of these knife-blades are seated within depressions or recesses o in the upper surface of the guide-fingers O, the walls of the depressions preventing lateral play of the blades relative to 5 the fingers and rivets or pins o', passing through the blades and perforated ears o'' on the fingers, serving to fasten the lower ends of said blades in their respective recesses or seats.

15 Near the upper ends of the blades Q and arranged transversely thereto I secure a cutter-bar R, rigid with the forward face of the beam P, the effective or operating portions of the cutter-bar being intermediate the guide-fingers and across the space therebetween. As the stalks pass through the ways K their attached or lower ends first enter the spaces between the guide-fingers and as the machine moves forward are drawn therethrough, 20 whereby the ears are caught between the fingers and guided by the diverging walls thereof to the cutter-bar R, which cuts the same from its butt and stalk when the detached ear is in position for the succeeding manipulation, as will presently appear. The purpose of the knife-blades Q is principally to cut up and lessen the hindrance offered to the progressive movement of the machine by foreign matter or stalks disposed across the path 25 of movement of said blades and transversely of the line of travel of the machine, also to keep the ears straight as they are cut from the stalks. It is to be noted that as the machine travels in a forward direction and the 30 ears are engaged by the guide-fingers O the separation of said ears from their stalks is strongly resisted by reason of the stalks holding fast to the ground, so that when the ears are cut from the stalks by the cutter-bar R they project forwardly at substantially right 35 angles to the cutter-bar in position to have their pointed ends caught by some of the teeth n, disposed around the periphery of the rotary carrier N. This effects a reversal of 40 the separated ears endwise, whereby they are carried through the machine point first.

The first husking operation may now be described. The ears being carried in an upward direction by the carrier N, as indicated by the arrow, Fig. 2, the same are engaged by a toothed roller S, rotating in the direction of the arrow, same figure, whereby the ears are elevated or pushed upwardly into the space between rotary husking devices T 45 and the carrier N. This pushing-roll has several flanges s in line with the flanges M on the carrier N, whereby the proper alinement of the ears is maintained. One rotary husking device T is disposed directly opposite to 50 each space between the peripheral flanges of

the rotary carrier, and they are independently supported and also independently actuated. The peculiar character of the teeth t of the husker is perhaps best seen in Fig. 4, where said teeth are illustrated as being 55 formed upon an arc conforming as near as possible to the average curvature of one side or half of an ear, whereby the husks on the side or half of the ear presented to the teeth of the husking device will be firmly grasped 70 thereby and torn from the ear as the carrier rotates away from the same, the husking devices of course rotating in an opposite direction, Fig. 5. The husking devices T are, as previously stated, yieldably supported, whereby they 80 may automatically approach closer to or recede from the rotary carrier to accommodate ears of different thickness, the initial adjustment of the parts being of course for the smaller-sized ears. The yieldable bearings 85 comprise a main supporting-plate U, Figs. 5 and 8, secured to the frame A of the machine and carrying a series of rearwardly-disposed tubular sleeves or housings u, one for each husking device, within which slidable 90 bearing-boxes u' for said husking devices work back and forth. These boxes are guided in their movement by lugs u'', fitting the slots u''' in the sleeves. The movement of the bearing-boxes in a rearward direction is resisted by springs u⁴, bearing at one end against the boxes and at their opposite end against an adjustable plug or screw u⁴, threaded into the open end of the sleeves, and through the medium of which the tension of the springs 95 is regulated. u⁵ represents stems on the bearing-boxes guided by longitudinally-disposed apertures u⁶ in the plugs u⁴. The husking devices are driven by means of sprocket-chains V, operated from gears v on a common drive-shaft v' and engaging the centrally-disposed gears v'' of the husking devices. The teeth of the husking devices are cleaned by the teeth of the pushing-roll S, and also by depending teeth v³ on the supporting-plate U. It may happen that some of the ears separated from the stalks are too short 105 to be engaged by the teeth n of the rotary carrier N, and in this event such short ears are simply pushed upwardly by the succeeding ears and forwardly by inclined guides W, arranged immediately above the cutter-bar, until the same are caught by the teeth n or the teeth of the pusher-roller S. Teeth w at the upper edges of the guides W serve to 110 prevent the short ears escaping rearwardly thereover and also constitute cleaners for the pusher-roller. The ears having now been stripped of the husks on one side thereof are carried upwardly and around the top of the 115 machine by the rotary carrier N until they approach the husking instrumentalities for the opposite side of the ears mounted at the forward end of the main portion of the machine and which will now be described, said 120 :30

ears having in the meantime been held in place upon the teeth of the carrier by freely-mounted gravity pressure-rolls X, the shafts x of which work in slots x' in arched side members x'' of the frame of the machine.

With reference to Figs. 2 and 6, Y designates a husking device mounted relatively close to the rotary carrier N and fixed against bodily movement relative thereto to prevent the ears on the carrier passing therebetween. This husking device extends entirely across the machine and is provided with properly-separated husking-teeth y of the same general character as the teeth t of the devices T, hereinbefore described. The husking device Y rotates in the direction of the arrow, Fig. 5, in opposition to a rotary feeding and pressing device Z, rotating in a contrary direction, one arranged opposite each peripheral set of teeth on the rotary carrier. The yieldable bearings for the feeding and pressing devices are represented at z and the common supporting-plate therefor at z', it being unnecessary to go further into the detail of these, as they are the same in structure as the corresponding elements hereinbefore defined in connection with the husking devices T. As the carrier approaches that part of the machine last referred to the centrifugal force incident to the rapid movement of the carrier will cause a separation of the ears therefrom, and said ears coming in contact with the foremost roller X will be guided thereby to the feeding and pressing devices Z, the headed pins z'' of which will grab the ears and force them between the same and the husking device Y, the result being that the under or unhusked half or side of the ears will be presented to the teeth of the husking device Y and stripped from the ears thereby. The removed husks are carried around by the device Y and falling upon the inclined teeth and plate (designated, respectively, at 2 and 3) are delivered to a chute 4, inclining outwardly and downwardly toward both sides of the machine, whereby the husks are conducted to the ground. The chute is mounted upon the side bars E of the stalk-bending device, so that the vibration thereof incident to the engagement of the teeth T with the ground will shake the husks and cause a proper feed thereof through said chute to either the one or the other side of the machine. The cleaned or husked ears fall from between the husking device Y and the feeding devices Z into a hopper 5 therebeneath arranged at the rear end of a forwardly-extending upwardly-inclined endless elevator 6, adapted to carry the corn from the machine and drop it into the wagon-body in front of the same or into any other receptacle provided therefor. The supporting-frame 7 for the elevator rests upon the upper ends of the uprights 8.

Chains 9, engaging sprockets 10 on the axle 11 of the rotary carrier N and corresponding sprockets 12 on the axle 13 of the traction-wheels B on opposite sides of the machine, transmit the driving motion from said traction-wheels to said rotary carrier. A similar chain 14, engaging a sprocket 15 and a sprocket 16, rigid with the shaft 11 and adjoining one of the sprockets 10, imparts the proper movement to the drive-shaft v' for the husking devices T. At the opposite end of the shaft s' I provide another sprocket 17, operating through the medium of a chain 18 and sprocket 19 to rotate the husking device Y, said husking device in turn effecting the operation of the feeding and pressing devices Z by means of chains 20, running from the husking device to a drive-shaft 21, mounted at the forward upper end of the frame A, and a chain 22, running from said shaft to the shaft of each of the feeding and pressing devices Z, suitable sprockets being provided for this purpose. Any convenient means may be utilized in operating the endless elevator 6. The rotary carrier hereinbefore referred to is shown as hexagonal, the flat surfaces of which permit the corn carried thereby to lie flat thereon; but it is obvious that any - shaped carrier found practical—for instance, one having a greater or less number of sides—may be substituted for that shown. The forward pitch or inclination of the frame of the machine enables the proper mounting and disposition of the parts, while greatly decreasing the size and number of the parts of the same which would otherwise be required. It also enables the corn to be continually carried forwardly after leaving the initial husking devices and to shoot forwardly and downwardly by centrifugal force and gravitation to the second or final husking device, as before described.

23 represents clutches of any convenient character for drawing the sprocket-wheels 12 into and out of operative relation with the traction-wheels B.

Another feature of importance, not heretofore observed, is the disposition of the teeth n on the periphery of the rotary carrier N. In Fig. 3 it will be seen that these teeth are arranged in pairs, the teeth of each pair being so separated that they will not engage the center or thickest portion of the ears, but rather at points a little to the sides of the longitudinal center, which will give a firm hold on the husks and enable their ready removal without otherwise damaging the corn.

It is to be understood that although certain disclosures have been made herein and a special embodiment of the invention illustrated the invention is susceptible of many other embodiments. It is also appreciated that changes and alterations may be made in the various features and arrangements of

parts of the machine shown in the drawings without departing from the spirit of the invention.

Having thus described the invention, what is claimed as new, and desired to be secured by Letters Patent, is—

1. In a machine of the character described, a stalk-bender, means in rear thereof for alining the stalks longitudinally of the machine, means in rear of said alining means for separating the ears from the stalks, and means for adjustably supporting the bender in advance of the alining means.

2. In a machine of the character described; a stalk-bender arranged to bend the stalks into a position substantially parallel with the ground prior to the removal of the ears from the stalks, said bender being provided with side plates adapted to prevent lateral movement of the stalks, in combination with ear-removing means arranged in rear of said bender.

3. In a machine of the character described, a stalk-bender arranged to bend the stalks into a position substantially parallel with the ground provided with means for guiding the stalks into longitudinal alinement with the machine while in their bent condition and prior to the separation of the ears from the stalks, in combination with ear-removing means arranged in rear of said bender.

4. In a machine of the character described, means for bending the stalks into a position substantially parallel with the ground, means forming a guideway in rear of said bender for alining the stalks while in bent condition, and means adjacent to said guideway for separating the ears from the stalks.

5. In a machine of the character described, means for bending the stalks down to a position substantially parallel with the ground, guide-fingers arranged longitudinally of the machine for engaging the ears of a stalk when in bent condition, and means for cutting the ears from the stalk arranged transversely of the guide-fingers.

6. In a machine of the character described, guide-fingers for engaging the ears of a stalk, a cutter operatively associated therewith for removing the ears from the stalk, and knife-blades on the fingers disposed in vertical planes, the forward edges of said knives constituting their cutting portions.

7. In a machine of the character described, guide-fingers for engaging the ears of a stalk, a cutter operatively associated therewith for removing the ears from the stalk, and knife-blades removably mounted upon the fingers disposed in vertical planes, the forward edges of said knives constituting their cutting portions.

8. In a machine of the character described, means for bending the stalks toward the ground, in combination with instrumentalities

independent of the bending means for separating the ears from said stalks while in bent condition and for husking said ears.

9. In a machine of the character described, means for bending the stalks toward the ground, said bender being arranged to pass over said stalks, in combination with instrumentalities arranged in rear of said bender for separating the ears from the stalks while in bent condition.

10. In a machine of the character described, an approximately cylindrical rotary carrier, a guideway leading thereto for alining the stalks, means adjacent to said way for separating the ears from said stalks, and means operating in conjunction with the carrier for husking said ears.

11. In a machine of the character described, an approximately cylindrical carrier, means for engaging the stalks, means for separating the ears from said stalks, and means operating in conjunction with the carrier for husking said ears.

12. In combination with a rotary carrier, means for separating the ears from a stalk, husking instrumentalities above said separating means, and means for pushing the separated ears upwardly toward the husking instrumentalities.

13. In combination with a rotary carrier, means for separating the ears from a stalk, husking instrumentalities above said separating means, and a pusher-roll for forcing the ears upwardly toward the husking instrumentalities.

14. In combination with a rotary carrier, means for separating the ears from a stalk and for presenting the points thereof to the carrier, husking instrumentalities, and means for pushing the separated ears upwardly toward the husking instrumentalities.

15. In combination with a rotary carrier, means for separating the ears from a stalk and for presenting the points thereof to the carrier, means for forcing the shorter ears toward the carrier, and means operatively associated with the carrier for husking said ears.

16. In a machine of the character described, means for separating the ears from the stalks, and separated guide-fingers for the stalks projecting downwardly and rearwardly relative to the direction of travel of the machine and toward the separating means forming a way leading toward the said separating means.

17. In a machine of the character described, a stalk-bender having between its sides a space for the stalks, said space tapering in a rearward direction relative to the line of travel of the machine, in combination with means in rear of said bender for separating the ears from the stalks.

18. In a machine of the character described,

means for separating the ears from a stalk comprising a cutter-bar, guide-fingers leading thereto, knife-blades on the guide-fingers disposed in vertical planes, and means for securing said blades in place including a bracket embracing the opposite sides thereof and connected thereto.

In testimony whereof I affix my signature in presence of two witnesses.

IRVING J. BALL.
